MIXER

Thomas J. Laird, Buffalo, N. Y., assignor to T. J. Laird Equipment Corporation, Buffalo, N. Y., a corporation of New York

Application November 12, 1948, Serial No. 59,486

2 Claims. (Cl. 259—96)

1

This invention relates to apparatus for mixing paint enamel and analogous material.

The problem of thoroughly mixing and dispersing pigments in vehicles and solvents in the manufacture of paint and enamel is one which has been the subject of very many experiments and a vast amount of research and numerous devices for accomplishing this general purpose with varying degrees of efficiency and satisfaction have been evolved. This problem is accentuated by the fact that the general run of pigments and pigmenting materials are used in an initial semi-solid state and are very tenacious and difficult to break up and blend with the liquid vehicles and solvents, particularly since a very complete dispersion of the pigmenting material in the vehicle or carrier is required.

Also, the percentage composition of the semi-solid pigmenting material is relatively high in the ultimate paint mixture as compared with various other mixing processes in the industrial and chemical arts generally. Often the vehicles themselves, such as various drying oils and varnishes, are themselves quite viscous which further contributes to the difficulty of attaining a thorough mixing and dispersion within practical and economic limitations.

The present apparatus is found by actual demonstration to thoroughly mix and disperse paint compositions, which include principally semi-solid pigmenting material and liquid vehicles or carriers, in a surprisingly thorough manner and in a period of time only a fraction of that generally required in mixers of the prior art operating under generally similar conditions upon similar paint compositions.

The apparatus of the present invention has various features of novelty which are brought together to produce, in combination, the desired end result of thorough mixing and dispersion of the paint ingredients in a minimum of time. However, one of the important features in and of itself is the relationship of the main agitator or rotor of the mixer and a slotted stator which shrouds it intimately in such manner that material is mixed at the point of cooperation of the two elements with what appears to be a shearing mixing action which produces full and complete dispersion of the pigmenting materials in the vehicles in a time heretofore unattainable under other generally similar conditions.

A complete and specific embodiment of the invention is illustrated in the accompanying drawings and described in detail in the following specification. However, it is to be understood

2

that this embodiment is set forth by way of example only, and that the invention is not limited excepting as defined in the appended claims.

In the drawings:

5 Fig. 1 is a vertical cross-sectional view centrally through a mixing vessel embodying one form of the present invention;

Fig. 2 is a top plan view thereof with the cover element removed;

10 Fig. 3 is a vertical fragmentary cross-sectional view on a larger scale taken through the mixing elements themselves; and

15 Fig. 4 is a fragmentary top plan view of the stator element shown partially in cross-section for added illustration and with a portion of the mixing rotor indicated.

Throughout the several figures of the drawings, like characters of reference denote like parts, and the numeral 10 designates a generally cylindrical 20 round bottomed mixing vessel which is provided with a detachably secured cover element 11 of any conventional form. The lower portion of vessel 10 is surrounded by a water jacket 12 in which cooling liquid may be circulated to absorb a considerable portion of the heat generated by the rather intense mixing action of the apparatus. Referring particularly to Fig. 3, a flanged plate 14 which supports the mixing implements is secured in a central opening at the bottom side of vessel 10 in any desired manner, as by means of the bolt and nut connections indicated at 15 in Figs. 1 and 3.

25 A bearing sleeve 17 is secured centrally of plate 14 by welding or the like and extends downwardly therefrom. At the upper portion of sleeve 17 there is a circular nut element 18 which screws into plate 14 as shown in Fig. 3 and provides an upper seat for a series of packing elements 19 which may comprise aluminum foil packing rings of conventional construction. Immediately below the packing rings there is a bronze bushing designated 20 and below that in Fig. 3 is a double row anti-friction ball bearing 21. The several packing rings 19, bushing 20 and bearing 21 are all retained in properly assembled and adjusted position in bearing sleeve 17 by means of an externally threaded retaining ring 22 which threads into the lower end of sleeve 17 and engages the outer race of ball bearing 21.

30 35 40 45 50 The foregoing bearing construction provides sealed bearing for a mixer shaft 23 which is rapidly rotated from beneath vessel 10 and jacket 12 by any desirable motive means which may act through a drive pulley 24. Mixer shaft 23 has a mixing rotor 24 fixed for rotation therewith im-

mediately above plate 14, as by means of a Woodruff key 25 and a set screw 26 in the hub of rotor 24. The blades of roller 24 are curved as viewed in plan, see Fig. 2, so as to present slightly trailing outer edge portions, as indicated fragmentarily in Fig. 4. The rotation of rotor 24 will be clockwise as viewed in Fig. 2. A stator element 28 which is illustrated in Figs. 3 and 4 comprises an annular disc having a concave recess formed in its under surface to receive rotor 24. The contours of the recess in stator element 28 and rotor 24 are complementary, as appears from Fig. 3.

Radially beyond rotor 24 stator element 28 has an annular ring portion 31 provided with a series of outwardly extending slots 32. The outer ends of the blades of rotor 24 are arcuate and concentric with the inner periphery of ring portion 31 of the stator element as shown in Fig. 4 and rub intimately against the inner periphery of ring portion 31 and thus force material through slots 32 by a combined centrifugal, squeezing and shearing action which appears to produce a much quicker and more efficient distribution and dispersion of paint materials than as heretofore been obtainable.

The slots 32 in the form shown in the present embodiment are not radial but slant in a clockwise direction from the inner periphery to the outer periphery of ring portion 31. As shown in detail in Fig. 4, the arcuate outer ends of the impeller blades have a considerable area of engagement with the inner periphery of ring portion 31 of the shroud element 28 whereby the impeller exerts a broad squeezing and shearing action against such inner periphery.

Referring to Fig. 3, an annular chamber 35 of generally triangular cross-section is provided at the upper side of shroud element 28 and may be formed by welding or brazing an inverted V ring 36 to the top of shroud element 28. This provides a cooling chamber in intimate association with the mixing device itself and also provides an entry throat to the mixing rotor from above. In Fig. 3 it will be noted that one of the screws 38 which holds shroud element 28 to plate 14 has an opening thereto and an inlet passage 39 leads from the upper end of the screw into chamber 35. A similar diametrically opposite screw and passage is indicated at 40 in Fig. 4 which provides an outlet passage and a conduit 41 in chamber 35 leads from the upper end of the outlet passage, at the upper surface of shroud 28, to the upper part of chamber 35.

Cooling water is introduced through opening 38 by means of a conduit 42 leading therefrom as shown in Fig. 1 and water discharged from conduit 41 and outlet passage screw passes from the mixer as by means of a conduit 43. It will be seen from the foregoing that cooling water is introduced from the bottom of chamber 35 and taken off at the top where the water temperature would naturally be greatest. The inlet conduit 42 may be connected with any water supply under pressure such as an ordinary city water supply.

The upper end of mixing shaft 23 is provided with an impeller 45 which rotates with rotor 24 and tends to preliminarily break up the pigment and force it downwardly toward the throat disposed concentrically within cooling chamber 35.

A series of baffle plates are provided along the interior walls of vessel 10 and, as shown clearly in Figs. 1 and 2, each baffle comprises a pair of plates 50 and 51 which extend generally parallel

to the inner wall of vessel 10, plate 50 being spaced inwardly from the wall and plate 51 being spaced somewhat inwardly from plate 50. Each pair of plate elements 50 and 51 is fixed to a pair of mounting pins 52 and 53 which are welded or otherwise fixed to the interior wall of vessel 10. One plate 50 is fixed to one side of a pair of rods 52 and 53 as by welding or the like, and the other plate 51 is fixed to the opposite sides of rods 52 and 53 so that the baffle plates of each pair are offset in a direction circumferentially of the vessel by a distance equal substantially to the diameters of pins 52 and 53.

What is claimed is:

- 15 1. Dispersion apparatus comprising a vessel and dispersion means therein comprising a stator and a rotor disposed therein, said stator comprising upper and lower discoidal portions lying closely adjacent the upper and lower surfaces of the rotor and including a central opening for ingress of material to be dispersed, said stator having an annular portion extending between the upper and lower discoidal portions and about the rotor, said rotor having outwardly projecting blades proportioned to terminate in relatively close juxtaposition to the inner periphery of the annular portion of the stator, said annular portion having a circumferential series of outwardly extending passages of relatively narrow cross-section as compared with their outward extent, and an axial displacement impeller disposed outside of said central opening and fixed for rotation with the rotor for urging material toward said central opening.
- 20 2. Dispersion apparatus comprising a vessel and dispersion means therein comprising a stator and a rotor disposed therein, said stator comprising upper and lower discoidal portions lying closely adjacent the upper and lower surfaces of the rotor and including a central opening for ingress of material to be dispersed, said stator having an annular portion extending between the upper and lower discoidal portions and about the rotor, said rotor having outwardly projecting blades proportioned to terminate in relatively close juxtaposition to the inner periphery of the annular portion of the stator, said annular portion having a circumferential series of outwardly extending vertical slots of relatively narrow width as compared with their outward extent, and an annular liquid heat exchange casing disposed against one of said discoidal portions to cool the rotor and the annular portion of the stator and form an intake throat to the rotor.
- 25 3. Dispersion apparatus comprising a vessel and dispersion means therein comprising a stator and a rotor disposed therein, said stator comprising upper and lower discoidal portions lying closely adjacent the upper and lower surfaces of the rotor and including a central opening for ingress of material to be dispersed, said stator having an annular portion extending between the upper and lower discoidal portions and about the rotor, said rotor having outwardly projecting blades disposed to trail relative to the direction of rotation and proportioned to terminate in relatively close juxtaposition to the inner periphery of the annular portion of the stator, said annular portion having a circumferential series of outwardly extending vertical slots of relatively narrow width as compared with their outward extent, and an annular liquid heat exchange casing disposed against one of said discoidal portions to cool the rotor and the annular portion of the stator and form an intake throat to the rotor.
- 30 4. Dispersion apparatus comprising a vessel and dispersion means therein comprising a stator and a rotor disposed therein, said stator comprising upper and lower discoidal portions lying closely adjacent the upper and lower surfaces of the rotor and including a central opening for ingress of material to be dispersed, said stator having an annular portion extending between the upper and lower discoidal portions and about the rotor, said rotor having outwardly projecting blades disposed to trail relative to the direction of rotation and proportioned to terminate in relatively close juxtaposition to the inner periphery of the annular portion of the stator, said annular portion having a circumferential series of outwardly extending vertical slots of relatively narrow width as compared with their outward extent, and an annular liquid heat exchange casing disposed against one of said discoidal portions to cool the rotor and the annular portion of the stator and form an intake throat to the rotor.
- 35 5. Dispersion apparatus comprising a vessel and dispersion means therein comprising a stator and a rotor disposed therein, said stator comprising upper and lower discoidal portions lying closely adjacent the upper and lower surfaces of the rotor and including a central opening for ingress of material to be dispersed, said stator having an annular portion extending between the upper and lower discoidal portions and about the rotor, said rotor having outwardly projecting blades disposed to trail relative to the direction of rotation and proportioned to terminate in relatively close juxtaposition to the inner periphery of the annular portion of the stator, said annular portion having a circumferential series of outwardly extending vertical slots of relatively narrow width as compared with their outward extent, and an annular liquid heat exchange casing disposed against one of said discoidal portions to cool the rotor and the annular portion of the stator and form an intake throat to the rotor.
- 40 6. Dispersion apparatus comprising a vessel and dispersion means therein comprising a stator and a rotor disposed therein, said stator comprising upper and lower discoidal portions lying closely adjacent the upper and lower surfaces of the rotor and including a central opening for ingress of material to be dispersed, said stator having an annular portion extending between the upper and lower discoidal portions and about the rotor, said rotor having outwardly projecting blades disposed to trail relative to the direction of rotation and proportioned to terminate in relatively close juxtaposition to the inner periphery of the annular portion of the stator, said annular portion having a circumferential series of outwardly extending vertical slots of relatively narrow width as compared with their outward extent, and an annular liquid heat exchange casing disposed against one of said discoidal portions to cool the rotor and the annular portion of the stator and form an intake throat to the rotor.
- 45 7. Dispersion apparatus comprising a vessel and dispersion means therein comprising a stator and a rotor disposed therein, said stator comprising upper and lower discoidal portions lying closely adjacent the upper and lower surfaces of the rotor and including a central opening for ingress of material to be dispersed, said stator having an annular portion extending between the upper and lower discoidal portions and about the rotor, said rotor having outwardly projecting blades disposed to trail relative to the direction of rotation and proportioned to terminate in relatively close juxtaposition to the inner periphery of the annular portion of the stator, said annular portion having a circumferential series of outwardly extending vertical slots of relatively narrow width as compared with their outward extent, and an annular liquid heat exchange casing disposed against one of said discoidal portions to cool the rotor and the annular portion of the stator and form an intake throat to the rotor.
- 50 8. Dispersion apparatus comprising a vessel and dispersion means therein comprising a stator and a rotor disposed therein, said stator comprising upper and lower discoidal portions lying closely adjacent the upper and lower surfaces of the rotor and including a central opening for ingress of material to be dispersed, said stator having an annular portion extending between the upper and lower discoidal portions and about the rotor, said rotor having outwardly projecting blades disposed to trail relative to the direction of rotation and proportioned to terminate in relatively close juxtaposition to the inner periphery of the annular portion of the stator, said annular portion having a circumferential series of outwardly extending vertical slots of relatively narrow width as compared with their outward extent, and an annular liquid heat exchange casing disposed against one of said discoidal portions to cool the rotor and the annular portion of the stator and form an intake throat to the rotor.
- 55 9. Dispersion apparatus comprising a vessel and dispersion means therein comprising a stator and a rotor disposed therein, said stator comprising upper and lower discoidal portions lying closely adjacent the upper and lower surfaces of the rotor and including a central opening for ingress of material to be dispersed, said stator having an annular portion extending between the upper and lower discoidal portions and about the rotor, said rotor having outwardly projecting blades disposed to trail relative to the direction of rotation and proportioned to terminate in relatively close juxtaposition to the inner periphery of the annular portion of the stator, said annular portion having a circumferential series of outwardly extending vertical slots of relatively narrow width as compared with their outward extent, and an annular liquid heat exchange casing disposed against one of said discoidal portions to cool the rotor and the annular portion of the stator and form an intake throat to the rotor.
